US00D962010S

(12) **United States Design Patent** (10) **Patent No.:** **US D962,010 S**
(45) **Date of Patent:** **** Aug. 30, 2022**

(54) **DIVIDER ACCESSORY**

(71) Applicant: **YETI Coolers, LLC**, Austin, TX (US)

(72) Inventors: **Steve Charles Nichols**, Austin, TX (US); **Andy Bondhus**, Austin, TX (US); **Tobias Hotchkiss**, Austin, TX (US); **Mark Carlson Rane**, Austin, TX (US); **John Loudenslager**, Austin, TX (US); **Derek G. Sullivan**, Austin, TX (US)

(73) Assignee: **YETI Coolers, LLC**, Austin, TX (US)

(**) Term: **15 Years**

(21) Appl. No.: **29/800,139**

(22) Filed: **Jul. 19, 2021**

Related U.S. Application Data

(63) Continuation of application No. 29/760,880, filed on Dec. 4, 2020, now Pat. No. Des. 925,991, which is a (Continued)

(57) **CLAIM**

The ornamental design for a divider accessory, as shown and described.

DESCRIPTION

FIG. 1 is a top, front, right perspective view of a divider accessory showing our new design;

FIG. 2 is a bottom, rear, left perspective view of the divider accessory thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof;

The broken lines immediately adjacent to the shaded area define the bounds of the claimed design and form no part thereof. The broken lines depicting the remainder of the divider accessory show features that form no part of the claimed design.

1 Claim, 6 Drawing Sheets

Related U.S. Application Data

continuation of application No. 29/757,384, filed on Nov. 5, 2020, now Pat. No. Des. 929,814, which is a continuation of application No. 29/673,074, filed on Dec. 11, 2018, now Pat. No. Des. 907,445.
